RUBBER SHEETING

Janet C. Kilner, Romeo, Mich., assignor to Dow Corning Corporation, Midland, Mich., a corporation of Michigan

Application October 7, 1948, Serial No. 149,010

Term of patent 14 years

(Cl. D87—3)

To all whom it may concern:

Be it known that I, Janet C. Kilner, a citizen of the United States, residing at Romeo, in the county of Macomb and State of Michigan, have invented a new, original, and ornamental Design for Rubber Sheet, of which the following is a specification, reference being had to the accompanying drawing, forming part thereof.

Figure 1 is a plan view of a piece of rubber sheeting, showing my new design.

Figure 2 is an edge view of the piece of rubber sheeting shown in Figure 1, wherein the design appears as ridges upon the surface of the sheeting.

I claim:

The ornamental design for rubber sheeting, as shown and described.

JANET C. KILNER.
